SLIPPER HAVING WINGS INTEGRAL WITH SOLE

Masanori Yamada, St. Thomas, Ontario, Canada

Application August 19, 1949, Serial No. 111,211

1 Claim. (Cl. 36—9)

1

The invention relates to improvements in sanitary slippers as described in the present specification and illustrated in the accompanying drawings which form a part of the same.

The invention consists essentially of the novel features of construction as pointed out broadly and specifically in the claims for novelty following a description containing an explanation in detail of an acceptable form of the invention.

The objects of the invention are to furnish sanitary slippers which may be easily set up ready for use from a flat blank; to make a slipper from paper or the like, thus rendering the same exceptionally inexpensive so as to permit the user to discard the slippers after they have been used a few times; to promote sanitary conditions in the home or institutions by providing inexpensive sanitary slippers which may be used in bathrooms, steam baths, and for going to and from indoor swimming pools and the like; to furnish folding slippers which may be easily carried when travelling and yet which will be simple to set up ready for use; to facilitate forming paper slippers and the like from a single blank of material in which the same is provided with suitably interlocking means for holding the slipper in a set up position; and generally to provide sanitary slippers which will be inexpensive, easy to put on and comfortable to wear.

In the drawings:

Figure 1 is a plan view of the blank for the slipper before the same has been folded.

Figure 2 is a plan view of the inner sole for the slipper.

Figure 3 is a plan view showing the blank partially folded up to form the slipper.

Figure 4 is a plan view showing the slipper in a set up position ready for use.

Figure 5 is a perspective view showing the slipper in a set up position similar to that illustrated in Figure 4 and ready for use.

Like numerals of reference indicate corresponding parts in the various figures.

Referring to the drawings, the blank as indicated by the numeral 10 is cut from a single sheet of material and comprises a bottom wall or sole portion 11 having wing or flap portions 12, 13, and 14 extending outward therefrom and being integral therewith. The wing or flap portion 12 extends outward from the one side of the foot portion of the bottom wall 11. A retaining flap 15 extends outward from the front portion of the wing or flap portion 12 and is adapted to be folded inward towards the latter. This wing or flap portion 12 has slots 16 and 17 cut

2

in same. These slots 16 and 17 are actually made by cutting arcuate slits in the material and then bending the portion extending inward from the arcuate slit slightly downward so as to facilitate the insertion of locking lugs thereinto. This wing 12 extends outward from the bottom wall 11 and is arcuately shaped along the edge thereof, being wider in the central portion of same.

The wing or flap portion 13 extends outward from the bottom wall 11 towards the front thereof and at the opposite side to that of the wing 12. A locking lug 18 is formed in the wing 13 towards the outer portion thereof by cutting a U-shaped slit in the material and then bending the portion inside this U slightly upward while the blank is still in a flat position. This locking lug 18 is integral with the wing 13 and extends inward towards the bottom wall or sole portion 11. This wing 13 extends outward from the bottom wall 11 and is arcuately shaped along the edge thereof, being wider in the central portion of same, and is provided with a small hole 18A located adjacent the locking lug 18, between the lug and the top edge of the wing.

25 An elongated flap or wing portion 14 extends outward from the bottom wall or sole portion 11 and is located directly to the rear of the wing portion 13. A locking lug 19 is located in the outer portion of this wing or flap portion 14 and extends inward towards the bottom wall 11 in a similar manner to that of the locking lug 18. A small hole 19A is provided in the flap 14 adjacent the locking lug 19, corresponding in position to the hole 18A in the wing 13. This wing 14 extends outward in an arcuate manner at the extreme ends of same and the side portions curve inwardly.

30 The bottom wall 11 has a locking lug 23 located in the heel portion thereof. This locking lug is similar to the locking lugs 18 and 19 in the wings and it extends forward and is slightly raised at the free end of same.

The insole 21 shown in Figure 2 is cut from a flat piece of material and provided with a slot 45 22 in the heel portion thereof. This slot 22 is cut and shaped in a similar manner to that of the slots 16 and 17 in the wing 12.

In folding the sanitary slipper ready for use, the insole 21 is placed over the bottom wall 11 and the locking lug 23 engages with the slot 22 thus securing the inner sole to the bottom wall at the rear thereof. The wing 12 is folded upward and the retaining flap 15 on the front portion thereof folds under the front end of the inner sole. A paper fastener 24, or any other

suitable locking member, engages through the hole 18A in the wing 13 with the head of same on the inside of the wing. The prongs of the fastener are spread to retain it to the wing, while the slipper is in its open or unfolded state.

After wing 12 has been folded to the inner sole the wing 13 is folded over the wing 12 and the locking lug 18 engages in the slot 16, thus securing the two wings together. The elongated wing 14 is folded over the wing 13, the prongs 10 of the fastener 24 first being closed together, the fastener engages through the hole 19A and the prongs of same being opened or spread to be held to the wing 14, locking the wing 14 to the wing 13, the locking lug 19 engaging in the slot 17 in the wing 12. The slipper is now secured in a completely set up position and as the foot is placed therein, the same will take its shape.

What I claim is:

In a slipper, a single sheet of a flexible fabric 20 being cut out to form the bottom and uppers of the slipper, said uppers comprising a first wing, a second wing and a third wing, said first wing being at one side of the said bottom and said second and third wings being at the opposite side 25 of said bottom to that of said first wing, a retaining flap extending forward from the toe portion of said first wing and folding inward upon the setting up of said uppers, said first wing having a pair of slots of an arcuate formation 30 therein and the material of said wing same being bent outward along one side thereof, locking tabs formed in said second and third wings by cutting a portion of the same from the body 35 of each of the same, a locking tab integral with

said bottom similar to said locking tabs in said wings and extending forward from the rear portion of the bottom of the slipper, an inner sole having an arcuate slot cut therein toward the heel of same and adapted for engagement with said locking tab in said bottom, a fastening staple secured to said second wing, said first wing being overlapped by said second wing during the setting up of the slipper and said fastening staple engaging said first wing while said locking tab engages one of the slots in said first wing, and said third wing overlapping said second wing and the locking tab of said third wing engaging in the other slot in said first wing, thus holding the slipper in its set-up position.
